A. PARKER.

PUSH BUTTON FOR AUTOMATIC OVERLOAD.
APPLICATION FILED OCT. 27, 1919.

1,413,679.

Patented Apr. 25, 1922.

UNITED STATES PATENT OFFICE.

ARTHUR PARKER, OF HADDON HEIGHTS, NEW JERSEY, ASSIGNOR OF ONE-THIRD TO LEON G. BUCKWALTER, OF MERCHANTVILLE, NEW JERSEY, AND ONE-THIRD TO CHARLES REDDING, OF CLEMENTON, NEW JERSEY.

PUSH BUTTON FOR AUTOMATIC OVERLOAD.

1,413,679.

Specification of Letters Patent. Patented Apr. 25, 1922.

Original application filed July 15, 1919, Serial No. 310,985. Divided and this application filed October 27, 1919. Serial No. 333,569.

To all whom it may concern:

Be it known that I, ARTHUR PARKER, a citizen of the United States, residing at Haddon Heights, county of Camden, State of New Jersey, have invented a new and useful 5 Push Button for Automatic Overload, of which the following is a specification.

In a contemporaneously pending application filed by me on July 15th, 1919, Serial 10 No. 310,985, of which this application is a division, I have shown a novel construction 15 of automatic, overload, releasing switch for electrical tools, such as electric drills, reamers and the like, wherein I employ an electromagnet in series with the drill motor and contained within the drill handle, said automatic overload releasing switch being also 20 contained in said handle and adapted to be closed by a novel construction of a push button and its adjuncts having suitable connections to said switch.

My present invention relates more particularly to the push button and its adjuncts and its novel resetting mechanism in conjunction with means for limiting the upward 25 and downward movement of the push button, the latter being especially applicable to the operation of mechanism located near to or at a little distance therefrom.

It further consists of a novel construction 30 and collocation of an electric drill handle, containing both a push button and the principal mechanical and electrical elements coacting therewith, said push button having 35 a wooden or nonconducting spindle extending longitudinally from it to the switch mechanism actuated thereby, whereby all live parts outside of the handle are abolished and the opportunity for electrical 40 trouble is reduced to a minimum.

It further consists of the employment of 45 a push button having a guard around it which prevents accidental closing of the switch thus saving the operator and the machine from injury, said push button having also novel means coacting therewith for limiting its upward and downward movement.

It further consists of a novel construction 50 of push button and levers actuated thereby in conjunction with a tension device for automatically resetting said push button.

It further consists of a novel construction

of push button having a head, a shoulder thereunder and a pendant blade or flat stem, the latter being provided with a pin extending transversely therethrough, whereby the upward and downward movement of the push button is limited according to requirements. 55

It further consists of other novel features 60 of construction, all as will be hereinafter fully set forth.

For the purpose of illustrating my invention, I have shown in the accompanying drawing one form thereof which is at present preferred by me, since the same will be found in practice to give satisfactory and reliable results, although it is to be understood that the various instrumentalities of which my invention consists can be variously 70 arranged and organized and that my invention is not limited to the precise arrangement and organization of these instrumentalities as herein shown and described. 75

Figure 1 represents a longitudinal, sectional view of an electric drill handle having my novel construction of automatic overload releasing switch therein and showing also in elevation my novel construction of push button and its resetting mechanism. 80

Figure 2 represents a section on line 2—2 of Figure 1.

Figure 3 represents a perspective view of the push button and its pendant blade in detached position. 85

Figure 4 represents, on an enlarged scale, a plan view of the push button resetting mechanism, the push button being removed.

Figure 5 represents, on an enlarged scale, a side elevation of Figure 4, showing the 90 push button in position.

Similar numerals of reference indicate corresponding parts.

Referring to the drawings.

1 designates my novel construction of push 95 button, the same comprising a head 2, which has the pendant blade or flat stem 3, through which a pin 4 extends transversely. The push button is vertically movable in the hole 5 in the electric drill handle 6 and is provided with a guard 7, the construction and location of which will be apparent from Figures 1 and 2, the function of said guard being to prevent accidental depression of 100

the push button or closing of the switch thereby saving both the operator and the machine.

8 designates a flat, resilient plate or spring, 5 which is fixed or secured at one end as 9 to the interior of the drill handle 6 by means of screws 10 or other fastening devices, the opposite end of said spring 8 being bifurcated or provided with the forked arms 11, 10 which engage each side of the pendant blade or flat stem 3, as will be apparent from Figures 2 and 3, said arms 11 being below or in contact with the bottom shoulder 12 of the push button. The pendant blade or flat 15 stem 3 of the push button is guided in its up and down movement between the vertical plates 13 and in the space between said plates is fulcrumed at 14 an angular shaped resetting lever, composed of the three arms 20 or members 15, 16 and 17 which are preferably integral, the contour and collocation of said arms being understood from Figure 1. The upper end of the arm 15 is rounded as indicated at 18 and contacts with or is en- 25 gaged by the curved seat 19 in the bottom edge of the pendant blade or flat stem 3 of the push button, so that it will be seen that when said push button is depressed the arm 15 will be depressed and the arm 16 elevated 30 or rocked upwardly thereby exerting an upward pull also on the arm 17, which latter has connected thereto the end 20 of the spring 21, the opposite end 22 of the latter being connected to the arm 23 of the plate 35 or strip 24 which is secured within the bottom of the handle 6 by means of screws 25 or other equivalent fastening devices.

26 designates a yoke having the arms 27 extending rearwardly or to the left there- 40 of, the left hand ends of said arms being pivotally attached to the angular resetting lever at the junction of the arms 16 or 17 by means of the pin 28.

The yoke 26 is provided with a socket 29 45 in which is seated the end of the wooden rod or nonconducting spindle 30 whose opposite end is connected to a suitable portion of the actuating mechanism of my novel construction of automatic overload releasing switch 21, which is contained in the handle 6 or an extension thereof, said handle being secured to the casing 32 of an electric drill or reamer 33, which is provided with the electric motor 34, said casing forming the 50 field frame for the drill motor and as the electric drill per se forms no part of my present invention and may be of any conventional type as disclosed in patents Nos. 936,870 and 1,109,325, I deem it unnecessary 55 to describe the same in greater detail, as the general arrangement and collocation of the driving and driven mechanism and the reducing gearing common thereto, is well known to those skilled in the art.

60 I deem it also unnecessary to describe in

detail my novel construction of automatic overload, releasing switch, since the same per se forms no part of the present invention and is fully described in my opening application aforesaid, it being, however, 70 understood that the nonconducting rod or spindle 30 is connected through suitable mechanism to devices which close the switch contacts, suitable electromagnetic means being provided for automatically opening said 75 contacts when the drill motor becomes overloaded, the electromagnet being designated as 35, its core as 36, the latter having connected thereto the piston rod 37 of a shock absorbing device 38. The right-hand end of 80 the nonconducting spindle 30 is connected to a slotted cam member 38^x which coacts with suitable levers and tripping mechanism, which I have indicated generally as 39, but do not deem it necessary to describe the op- 85 eration of these parts in detail, as the same, per se, form no part of my present invention, it being understood that the right-hand end of the nonconducting spindle 30 is adapted to be connected generally to any element to 90 be actuated as a portion of a switch actuating mechanism of any desired type, my present invention being confined solely to the push button, its connections to the nonconducting spindle 30, and its resetting means. 95

The operation is as follows:

The parts normally appear as seen in Figures 1, 2 and 3, the bifurcated ends of the flat spring 8 engaging the shoulder 12 of the push button 2 and retaining the 100 latter normally in its uppermost position substantially as seen in Figure 1, the spring 21 holding the end 18 of the resetting lever in proper position with respect to the recess 19 of the blade 3. When the push 105 button is depressed, the arm 15 is depressed or rocked downwardly whereupon the arm 16 is rocked upwardly on its fulcrum 14 and the arms 27, the yoke 26 and nonconducting spindle 30 move longitudinally to 110 the right of the position seen in Figures 1 and 5, thereby operating the desired element to be actuated.

Upon the pressure of the operator's finger being removed from the push button the 115 extension of the spring 21 which was expanded when the push button was depressed will restore the parts to the position seen in Figures 1, 2 and 5. The pin 4 by its contact with the underside of the 120 bifurcated arms 11 will prevent the push button from an undue improper movement upwardly and its contact with the top edges of the plates 13 will prevent undue downward movement while in both its upward and downward movement said pendant blade or flat stem 3 is guided between the vertical parallel plates 13 as will be understood by reference to Figures 2, 4 and 5.

It will be understood from the foregoing 130

that the vertical movement of the push button imparts a horizontal or longitudinal movement to the nonconducting spindle 30 and that the tension of the spring 21 5 stores the parts to their normal position seen in Figures 1 and 2.

For convenience of assembling, I provide the handle member 6 with a screw cap or exterior left-hand closure 40 which upon 10 being removed renders the interior of the handle at once accessible and the parts comprising my novel push button mechanism and their adjuncts can be readily removed upon the removal of the screws 10 and 15 as will be evident.

It will now be apparent that I have devised a novel and useful construction of a push button for automatic overload which embodies the features of advantage enumerated 20 as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. As an improved article of manufacture, a push button having a shoulder on its 35 bottom, a pendant blade depending below said shoulder and provided with a curved seat, a spring pressed lever connected with said push button in the curved seat thereof for retaining said button in its upward position, and a transverse pin in said pendant blade.

2. As an improved article of manufacture, a push button having a shoulder on its bottom, a pendant blade or flat stem projecting below said shoulder and provided 45 with a curved seat, a spring pressed lever connected with said pendant blade in the curved seat thereof for retaining said button in its upward position, a transverse pin 50 in said flat stem, and means coacting with said pin for limiting the upward and downward movement of said push button.

3. In a device of the character stated, a tubular member having a push button movable therein, shoulders on said push button, a stem depending below said shoulder, a pin extending transversely through said stem, and a spring secured to the interior of said tubular member and having a bifurcated 60 end receiving said stem and located between said shoulders and pin.

4. In a device of the character stated, a tubular member having a push button movable therein, shoulders on said push 65 button, a stem depending below said shoul-

ders, a pin extending transversely through said stem, a spring secured to the interior of said tubular member and having a bifurcated end receiving said stem and located between said shoulders and pin, and means 70 for arresting the downward movement of said pin and push button.

5. A device of the character stated comprising, a tubular member, a push button movable therein, a spring pressed angular 75 lever secured to said tubular member and connected to said push button, and an insulating lever in said tubular member connected to said angular lever and movable longitudinally in said tubular member when said 80 push button is actuated.

6. A device of the character stated comprising, a tubular member, a push button movable therein, means for limiting the vertical movement of said push button, a spring 85 pressed angular lever secured to said tubular member and connected to said push button, and an insulating lever in said tubular member connected to said angular lever and movable longitudinally in said tubular member 90 when said push button is actuated.

7. The combination of a tubular member, a push button having a pendant blade provided with a curved seat in the end thereof movable in said tubular member at an angle 95 to the axis of said tubular member, an insulated spindle extending through said tubular member, connections common to said push button and spindle, and means for resetting said push button and simultaneously actuating 100 said spindle after pressure is removed from said push button.

8. A device of the character stated, comprising a tubular member, a push button movable therein at an angle to the axis of 105 said tubular member and having a shoulder on its lower portion and a pendant blade, a flat spring having one end secured to said handle and its other end bifurcated and having arms straddling said blade below 110 said shoulder, a pin extending transversely through said pendant blade, a pair of vertical plates below said stem between which said stem is guided, a longitudinally extending insulating spindle, and connections intermediate said push button and spindle for actuating the latter longitudinally.

9. In a device of the character stated, a hollow handle member, vertical plates secured to the interior thereof, a push button 120 having a pendant flat stem guided between said plates, a lever having one end in contact with the bottom of said stem, a tension device connected with the opposite end of said lever, an insulating spindle extending at an 125 angle to said push button, and connections from said spindle to said lever, whereby said push button, lever and spindle are actuated in unison.

10. In a device of the character stated, a 130

- tubular member, a push button movable therein and having a pendant stem, a recess in said stem, an angular resetting lever having an end engaging said stem, a tension device attached to the opposite end of said lever, a yoke, an insulated spindle secured in said yoke, and arms projecting from said yoke and pivotally secured to said angular lever.
10. 11. In a device of the character stated, a tubular member, a push button movable therein, and having a pendant stem, a recess in the bottom of said stem, an angular resetting lever having an end engaging said recess, a tension device attached to the opposite end of said stem, vertical plates within which said push button stem is guided, said lever being fulcrumed between said plates, a yoke having an end of an insulated spindle attached thereto, and arms projecting from said yoke and guided by said plates, said arms being pivotally attached to said lever.
12. In a device of the character stated, a tubular member, a push button movable therein and having a pendant stem, a recess in the bottom of said stem, an angular resetting lever having an end engaging said recess, a tension device attached to the opposite end of said stem, vertical plates within which said push button stem is guided, said lever being fulcrumed between said plates, a yoke having an end of an insulated spindle attached thereto, and arms projecting from
- 5 said yoke and guided by said plates, said arms being pivotally attached to said lever, in combination with a bar removable from said tubular member and carrying said vertical plates and tension device.
13. A device of the character stated, comprising, a tubular member, a push button angularly mounted therein, an insulated spindle extending through said tubular member, means within said tubular member for limiting the upward and downward movement of said push button, and resilient means mounted within said tubular member and connected to said push button for urging the latter to normal position.
14. A device of the character stated comprising, a handle, a push button angularly mounted and reciprocable within said handle, means for limiting the reciprocation of said push button, an insulated spindle reciprocable within said handle having one end connected to controlling mechanism, a pivotally mounted rigid connection between said push button and insulated spindle, and resilient means secured within said handle and to said rigid connection for urging said push button to normal position and for returning the insulated spindle to normal position through the medium of said rigid connection.

ARTHUR PARKER.

Certificate of Correction.

It is hereby certified that in Letters Patent No. 1,413,679, granted April 25, 1922, upon the application of Arthur Parker, of Haddon Heights, New Jersey, for an improvement in "Push Button for Automatic Overload," errors appear in the printed specification requiring correction as follows: In the grant, line 8, the name of the first-mentioned assignee was erroneously written and printed as "G. Buckwalter," whereas said name should have been written and printed as *Leon G. Buckwalter*; strike out present line 17 and insert *Arthur Parker, Leon G. Buckwalter, and Charles Redding, their heirs or assigns*; and that said Letters Patent should be read with these corrections therein that the same may conform to the record of the case in the Patent Office.

Signed and sealed this 16th day of May, A. D., 1922.

[SEAL.]

KARL FENNING,
Acting Commissioner of Patents.
